(57) **CLAIM**

The ornamental design for a portable electronic device, as shown and described.

DESCRIPTION

FIG. 1 is a top right front perspective view of a portable electronic device showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top left rear perspective view thereof;

FIG. 9 is an enlarged view of the encircled portion shown in FIG. 1;

FIG. 10 is an enlarged view of the encircled portion shown in FIG. 2;

FIG. 11 is an enlarged view of the encircled portion shown in FIG. 8;

FIG. 12 is the rear elevation view of FIG. 3 with the disclaimed circular camera, which is shown in dotted lines in FIG. 3 behind the oblique surface shading, removed;

FIG. 13 is the top left rear perspective view of FIG. 8 with the disclaimed circular camera, which is shown in dotted lines in FIG. 8 behind the oblique surface shading, removed;

and,

FIG. 14 is an enlarged view of the encircled portion shown in FIG. 13.

The short dash-dash broken lines in the figures represent unclaimed portions of the portable electronic device and form no part of the claimed design.

The short dash-dash broken lines that occur within the claimed surfaces in FIGS. 3, 8 and 11, showing of the circular camera, are superimposed on continuous surfaces and form no part of the claimed design.

(Continued)

The dot-dash broken lines encircling portions of the claimed design in FIGS. 1, 2, 8, 9, 10, 11, 13, and 14 that are illustrated in enlargements form no part of the claimed design.
